his Atty.

UNITED STATES PATENT OFFICE.

WILLIAM G. ANDERSON, OF BOSTON, MASSACHUSETTS.

ROTATING HEEL.

1,204,636.

Specification of Letters Patent.

Patented Nov. 14, 1916.

Application filed January 3, 1916. Serial No. 69,727.

To all whom it may concern:

Be it known that I, WILLIAM G. ANDERSON, a citizen of the United States, and resident of Allston, Boston, county of Suffolk, 5 Commonwealth of Massachusetts, have invented an Improvement in Rotating Heels, of which the following description, in connection with the accompanying drawings, is a specification, like characters on the drawings representing like parts in each of the 10 several views.

This invention relates to heel pieces of boots and shoes of a type adapted to be readily applied to a finished shoe or boot 15 after removing one or more of the outer heel lifts if desired, though a heel piece formed and applied in accordance with my invention may quite as readily be incorporated in the original manufacture of the shoe.

One important object of the invention is 20 to provide a heel piece adapted to be applied to the heel of a shoe in a manner so as to be shiftable so as to present constantly changing wear portions, and providing also 25 a construction whereby a cushioning resiliency effect is obtained from air cushions, these cushions being constituted by recesses that are adapted to serve also as suction devices to make a non-slipping tread.

A further object of the invention is to 30 provide an improved heel piece constituting a bottom or wear member mounted and applied to the heel of the shoe in a manner permitting constant shifting of position about 35 an axis of rotation whereby all peripheral portions of the heel piece are worn down equally so that running down of the heel to either side or at the back is prevented.

To this end I provide a heel piece of 40 circular disk form and of a suitable thickness to constitute a wear piece, and provide the same with a central countersunk wear washer preferably of metal through which is passed a pivot member which may be a 45 screw extending up into the heel and having its head engageable with said metallic washer to clamp the heel piece in place. In accordance with my invention this countersunk wear washer is of a diameter somewhat 50 greater than the normal dimension of the countersunk recess therefor whereby on crowding this wear washer into such countersunk recess the heel piece is distorted to a substantially dished form.

55 In practice I preferably form this heel of

rubber or like suitable material presenting a non-slipping surface.

The invention will be better understood from the following detailed description taken in connection with the accompanying 60 drawings and will be thereafter pointed out in the appended claims.

Referring to the drawings, Figure 1 shows in elevation a portion of a shoe with a heel piece constructed in accordance with my invention applied thereto, such heel piece being shown in central vertical section; the parts being shown as they appear when the weight of the wearer is resting on the heel piece; Fig. 2 is a bottom plan view of the 70 heel piece itself; Fig. 3 is an elevation of my improved heel piece detached, with the metallic washer associated therewith; and Fig. 4 is a view similar to Fig. 1, but showing the heel piece in normal downwardly 75 projected position.

A shoe or boot is indicated at S with a usual heel H which may be reduced in height as much as desired by the removal of 80 the outer lifts thereof for the application of my improved heel piece. The heel piece is indicated at 10 as a circular disk of suitable thickness to constitute a wear piece, for example, about three-eighths of an inch and formed preferably of rubber or rubber substitute, or like non-slipping material. This 85 wear piece disk is preferably of a diameter approximately equal to the width of the heel and is fitted in place so that at its rear side it forms a continuation of the heel outline, 90 while at the sides of the heel it also closely approximates a continuation downward of the heel sides. To better attain this result I preferably form the periphery of this disk 95 slightly tapering downward as indicated at 11. The central portion of the outer face of this heel piece is centrally recessed or countersunk as indicated at 12 to receive a washer 13 which is preferably metallic and sets within the outer face to some little extent. This 100 washer is centrally apertured to receive the head of a screw 14 which is engaged therewith to clamp the heel piece to the heel, this screw being for this purpose set up into the heel of the shoe. 105

In accordance with my invention the metallic washer 13 is made some little larger than the normal dimension of the central recess or countersink 12 and said recess is relatively deep, extending most of the way 110

through the heel piece leaving only a relatively flexible central diaphragm portion. Thus as the metallic washer is forcibly pressed into said recess the heel piece is distorted from its normal flat condition, as seen in Fig. 3, to a substantially dished form as seen in Fig. 4, with the convex side presented outward and leaving a substantial space between the central concave portion 5 of the heel piece and the heel of the shoe as indicated at 15 in Fig. 4. Thus as the weight of the wearer comes upon this heel piece it will yield to be pressed up against or relatively close to the heel of the shoe in its central portion as indicated at 15' in Fig. 1, thus imparting a substantial degree of resiliency. Then as the weight of the wearer is partly or wholly removed from the heel, 10 the heel piece tending to spring again outward, creates a suction which is exerted upon the central recess or cup space 12 wherefrom it results that the heel is prevented from slipping, this action being more pronounced on smooth surfaces such as polished floors or the like where the action 15 of the suction cup 12 will be more pronounced, and where of course this attribute is most desirable. In this way it will be understood that the central thin portion of 20 the heel piece through which the screw 14 passes, serves as a flexible diaphragm imparting resiliency to the heel and also attaining a suction cup effect to make the heel piece non-slipping. In use the heel piece 10 is thus held frictionally pressed 25 against the heel for its edges to lie substantially flush therewith but this frictional engagement is not such as to prevent more or less turning of the piece 10 about the 30 axis formed by screw 14 in use. Thus as the shoe equipped with this heel piece is worn, the piece 10 will shift constantly more or less about its central axis, presenting 35 constantly changing peripheral portions at the sides and back of the heel so that there is no possibility of uneven wear or running down of the heel at either side or the back thereof, but the wear on the heel piece will be substantially uniform until it is worn 40 out.

By the provision of the metallic wear washer 13, a relatively wide, reliable and permanent bearing hold of the axis screw 14 upon the heel piece is obtained, the metallic bearing between the washer 13 and the head of the screw permitting easy turning 45 of the heel piece in the angular shifting thereof, without any considerable dele-

terious wear as would be the case if the rubber of the heel piece were directly engaged by the head of the screw. Thus except for the provision of the wear washer 13, the heel piece would be apt to be torn off especially after a short amount of wear which would enlarge the hole therethrough around the screw. I have found that by the co-operative action of the metallic washer 13 with the head of the screw, when a proper clamping pressure is applied by turning up the screw, the frictional hold between the head 50 of the screw and the washer is just sufficient to provide proper resistance against too free turning of the heel piece, while permitting the same to shift gradually enough to present constantly changing wear portions as described.

I am aware that the invention may be embodied in other specific forms without departing from the essential attributes thereof, and I therefore desire the present embodiment to be considered as illustrative and not restrictive, reference being had to the appended claims rather than to the foregoing description to indicate the scope of the invention.

Having described my invention, what I claim as new and desire to secure by Letters Patent is:

1. A heel piece for boots or shoes, comprising a disk shaped resilient wear member having a central recess or countersink, a metallic washer larger than the normal diameter of said recess and arranged to be pressed thereto to distort said wear member to a dished form, and a pivot and securing member engaged with said washer and passed through said wear member to hold the same to a heel.

2. A heel piece for boots or shoes, comprising a disk shaped wear member of flexible rubber having its central portion formed with a relatively deep countersink leaving a relatively thin central diaphragm portion, a washer larger than the normal dimension of said countersink and arranged to be pressed thereto to distort said wear member to a dished shape, and a combined pivot and securing member passed centrally through said wear member and engaged with said washer to hold said wear member to the heel with a capability of angular shifting.

In testimony whereof, I have signed my name to this specification.

WILLIAM G. ANDERSON.
